UNITED STATES PATENT OFFICE.

CHARLES RUSSELL, OF SHARON HILL, AND ALBERT C. WELCHAUS, OF LANCASTER, PENNSYLVANIA.

ELECTRIC RAILWAY.

SPECIFICATION forming part of Letters Patent No. 629,211, dated July 18, 1899.

Application filed August 2, 1898. Serial No. 687,572. (No model.)

To all whom it may concern:

Be it known that we, CHARLES RUSSELL, residing at Sharon Hill, in the county of Delaware, and ALBERT C. WELCHAUS, residing at 5 Lancaster, in the county of Lancaster, State of Pennsylvania, citizens of the United States, have invented new and useful Improvements in Electric-Railway Systems, of which the following is a specification.

10 Our invention relates to improvements in electric railways; and it consists in the construction and arrangement of parts fully shown and described hereinafter and particularly pointed out in the claim.

15 Referring now to the drawings, Figure 1 is a cross-sectional view of a road-bed fitted with our invention. Fig. 2 is a side elevation of the same. Fig. 3 is an enlarged cross-sectional view of the trolley-rail, insulator, and 20 rail-guards.

25 Referring now to the drawings, A represents the ties of the road-bed, to which are secured the insulator-sockets 1. Situated in these insulator-sockets 1 are the plugs 2, to the upper ends of which are attached the insulators 3. The plugs 2 are connected in the 30 sockets 1 through the medium of a transverse pin 5, and the insulators 3 are of the petticoat design, having a projection at their upper ends, which projection is provided with a longitudinal slot to receive the depending web of the trolley-rail 4. The rail 4 is the conductor through which the electric current is transmitted, and situated in the slots 6 of 35 the insulators is sheet-rubber 11 to relieve the insulators from shocks through the vibration of the trolley-rail in the movement of the trolley thereover. This rail 4 is held in position by means of the bolts 10, which pass 40 through both the insulators and the rail, as illustrated, the bolts being themselves insulated from the rail by bushing of non-conducting material inserted through the rail and inclosing the bolts.

45 For the purpose of preventing anything coming in contact with the rail 4 we provide the wood rail-guards 9, which are situated at each side of the rail 4 and extending high enough thereabove and adjacent thereto to 50 prevent contact from above and extending

downward sufficiently to protect the lower edge of the trolley-rail, but a considerable distance above the ties to prevent an accumulation of dirt, snow, or water between the rail-guards. These rail-guards 9 are held in position by means of the chair-irons, which are essentially U-shaped in cross-section and which are placed any desired distance apart in order to securely and properly hold the said 55 guards, and the inner face of the upper ends 60 of these chairs are inclined inward, and the guard-rails are bound to the chairs against the upwardly-inclined surfaces by means of bolts or screws α , as best suits the requirement. The chairs are fastened to the ties in 65 any desired manner.

From this description it will be noted that the inclosing structure for the trolley-rail 4 is entirely above the ties A and between the rails 23, which support the car. The guards 70 are so situated that a very small space is left between their upper ends and extend downward to a point where they prevent accidental contact with the rail from above or below, while at the same time free intentional access 75 is had to the rail from above or below, and the lower edges of the rail-guards are considerably above the ties to allow snow and other obstructions to flow and to wash out below the trolley-rail, and there is sufficient 80 space to allow workmen to attend to the ties without removing the guards. The petticoat-insulators, constructed as herein shown and described, protect all parts, which produces an insulation adapted to carry a current of a 85 very high potentiality.

Having thus described our invention, what we claim, and desire to secure by Letters Patent, is—

An electric railway comprising a plurality 90 of transverse ties, the parallel rails adjacent each end thereof, insulator-sockets attached to some of the ties, petticoat-insulators supported by the said sockets and having upwardly-extending projections above the petticoats, the projections having vertical openings, a trolley-rail with a depending web fitting in said vertical openings, U-shaped guard-rail chairs attached to some of the ties 95 and having upwardly and inwardly extend- 100

ing faces, wood guard-rails connected to the inclined faces of the chairs with their upper edges projecting above and adjacent the upper edge of the trolley-rail and their lower edges projecting below the depending flange thereof but considerably above the ties, substantially as and for the purpose described. In testimony whereof we have hereunto set

our hands in the presence of two subscribing witnesses,

CHARLES RUSSELL.
ALBERT C. WELCHAUS.
